PAPER-MAKING MACHINE.

1,343,505.

Specification of Letters Patent. Patented June 15, 1920.

Application filed February 5, 1917. Serial No. 146,617.

To all whom it may concern:

Be it known that I, ANTON J. HAUG, a citizen of the United States, and resident of Nashua, county of Hillsborough, State 5 of New Hampshire, have invented an Improvement in Paper-Making Machines, of which the following description, in connection with the accompanying drawings, is a specification, like characters on the drawings representing like parts.

This invention relates to apparatus for separating from the liquid carrier the web forming material of pulp stock in paper manufacture. For purposes of illustration, 15 the invention is shown herein as applied to a decker, but certain features thereof have application to other types of pulp handling machines. The invention will be best understood by reference to the following description when taken in connection with the accompanying illustration of one specific embodiment thereof, while its scope will be more particularly pointed out in the appended claims.

25 In the drawings:

Figure 1 is a transverse, sectional elevation of a decker embodying one form of the invention;

Fig. 2 is an end elevation of the same 30 machine;

Fig. 3 is a plan view partially broken away of the decker shown in Fig. 1;

Fig. 4 is a longitudinal sectional elevation of the same decker;

35 Fig. 5 is an enlarged plan view showing certain of the couch roll adjusting connections;

Fig. 6 is a longitudinal sectional elevation of the connection shown in Fig. 5;

40 Fig. 7 is a detail showing the couch roll supports with the doctor adjusted for rotation of the couch roll in the opposite direction to that shown in Fig. 1; and

Fig. 8 shows the arrangement of belt 45 tightening arm when the cylinder and couch roll are reversely driven.

Referring to the drawings and to the embodiment of the invention therein illustrated, the decker therein shown comprises 50 a main frame or casing 1 forming a tank-like structure, the ends of which are closed by the end plates 2 and 3, the latter carrying suitable bearing supports for the shaft 4 which carries the screen or cylinder mold 5, the latter of any suitable or usual con-

struction. The cylinder 5 is driven by the driving gear 6 (Fig. 4), which latter meshes with a pinion (not shown) on the main driving shaft 7 (Fig. 3) to which driving power is imparted through the driving pulley 8, by any suitable means.

The cylinder 5 is adapted to rotate within the pulp tank 10, the bottom of which is formed by the casing wall 11, the pulp being fed to the tank through the stock supply inlet 12 (Fig. 1) where it passes over a perforated plate 13 which helps thicken the stock by extracting more or less water. The water passes through the plate into the water chamber 14, whence it is drained 70 away through any suitable passages. The ends of the pulp tank 10 are partly closed by the end plates 15 and 16 which prevent the stock from passing directly into the waste canal or chamber 17 beneath the stock tank 10. The end plates 15 and 16, however, have the exit openings 18 and 19 communicating the open ends of the screen drum with the interior thereof so that the strained water which has passed from the 80 tank through the screen flows through the exit openings in the end plates into the respective compartments at the opposite ends of the casing 2 and down into the waste tank 17 whence it is carried off through 85 suitable discharge passages indicated at 20, to any suitable receptacle which may be a save-all or some other device for saving the wood fiber.

The stock after being carried to the tank 90 through the pulp supply is deposited upon the rotary screen 5, the water passing through the screen and into the underlying waste tank 17 and the web of pulp thus formed on the screen being carried up and 95 removed by the couch roll 21 located above the screen. In the described embodiment of the invention the pulp is removed from the couch roll by the doctor 22 and caused to fall upon the underlying deflector plates 100 23 and 24, whence it passes into any suitable receptacle, such as the conveyer or tank 25 (shown in dotted lines) through which the thickened or deckered stock is withdrawn through any suitable means.

When machines of this type are shut down it has been a common practice to withdraw the residue of stock in the pulp tank, the residue withdrawn being emptied 105 on the floor where the machine stands and 110

carried with other waste into the sewer. Herein I have provided means whereby when the machine is shut down, the residue may be withdrawn and diverted into the 5 white water chamber, whence it may be conducted with the white water to a save-all or suitable device for saving the wood fiber. For this purpose the end plate 15 of the 10 pulp tank 10 (see Figs. 2 and 4) is provided with a sliding gate 26 adapted to open or close the orifice in the end plate, such gate being moved by means of the lever 27 having the easily accessible handle 28. In the normal operation of the 15 machine the gate is closed, the lever standing in the position shown in Fig. 2. When the machine is shut down the gate may be opened by moving the lever 27 to the right of the position shown in Fig. 2, thereby 20 permitting the pulp residue to flow from the tank 10 into the underlying white water chamber 17 and out through the discharge pipe 20.

Referring now to the support for the 25 couch roll 21 and the connections for adjusting the same to or from the cylinder, the couch roll is carried upon the couch roll shaft 30, opposite ends of which are mounted each in suitable bearings 31 which are 30 carried upon a tilting couch roll frame 32. Each tilting frame member 32 is supported for rocking movement upon pivot pins 33 (Figs. 2 and 4) which are carried by fixed 35 end supporting brackets 34, each bracket being bolted to the top of the corresponding end plate 15 or 16 and being split or bifurcated, the tilting frame member 32 being carried between the two portions of the bracket. It will be obvious that the 40 construction is such that the couch roll frame members 32 may be rocked about the pins 33 so as to bring the couch roll nearer or farther away from the face of the cylinder 5.

Suitable means are herein provided to 45 secure this adjustment of the couch roll, such means being specifically herein as follows: Each tilting frame member 32 is extended above the pivotal support 33 as shown in Fig. 4 to form an annular carrier 35 between 50 the two opposite sides of which is supported by means of suitable studs or trunnions 36 a small, cylindrical shaped member 37 which may be moved forward or backward to swing the tilting frame and adjust the 55 couch roll by means of the threaded rod 38 (see Figs. 5 and 6). The threaded rod carries at its end (see Fig. 6) the small piston or plunger 39 working within the chamber of the cylinder 37, there being provided a 60 second piston 40 facing the piston 39 and provided with the plunger 41 pressed into contact with the piston 39 by means of the compression spring 42.

In order that turning movement of the 65 screw shaft 38 may advance or retract the

tilted frame, the shaft has threaded engagement with a nut 43, which latter (as is shown at the left in Fig. 4 and in Figs. 5 and 6 where the annular carrier 35 is broken away) is supported upon studs 44 carried 70 in the two upright extensions 45 of the end supporting brackets 34.

To turn the screw shafts 38, each one of the latter has at its opposite end a bevel gear 46 meshing with a similar gear on the 75 transverse shaft 47, the latter being provided with hand wheels 48. By turning either hand wheel, both threaded shafts 38 are simultaneously turned, causing them to advance or retract in the threaded nuts 43. 80 When the screw shafts are retracted by suitable rotation of the hand wheels, the cylindrical members 37 are forcibly retracted, the tilting frame swung back and the couch roll lifted farther away from the cylinder 85 mold. When the screw shafts are advanced, the tilting frames are allowed to rock forward and the couch roll to descend, the wire in the cage bringing it into closer contact with the cylinder. There is thus provided 90 delicately adjustable means for positively raising the couch roll more or less and adjusting its distance from the cylinder, the adjustment being had by a simultaneous movement at each end of the roll so the roll 95 maintains its true parallel relation at all times to the cylinder.

Any abnormal pressure which occurs between the couch roll and the surface of the cylinder mold and which tends to lift the 100 couch roll is taken care of by the compression spring 42, such spring simply yielding and permitting the cylinder to slide back on the threaded shaft. The compression of the spring may be regulated by the threaded 105 head 49 in the end of the cylinder 37. The nut 43 is preferably mounted upon the studs 44 so as to be susceptible of a slight rocking movement, as is also the cylindrical member 37 upon the studs 36 so as to adapt the position of these parts to the adjustment of the couch roll supporting frame. 110

Herein the doctor 22 is so supported as to provide for an adjustment which maintains the angle or bevel of the doctor substantially the same with reference to the couch roll. To support the doctor each tilting frame member 32 is again prolonged above the annular carrying portion 35 to provide a horizontally extending boss 50 in which is 115 mounted a pin 51 carrying at the outside end the weighted arm 52 and at the inside end the hub 53 of the depending doctor supporting arm 54. The depending supporting arms 54 are longitudinally slotted at 55 120 (indicated in Fig. 1), open ends of the doctor blade 22 being secured to the arms by means of bolts 56 passing through the slots 55. By means of the bolts 56 passing through the slot 55 the position of the 125 130

doctor may be changed lengthwise the slot, the adjustment taking place along a line tangential to the couch roll so that the angle of the beveled edge of the doctor with relation to the couch roll remains substantially the same in any position of adjustment. The trunnion pins 51 which support the doctor being carried upon the tilting frame members 32, the doctor has an unvarying 5 relation with reference to the couch roll in the various adjusted positions of the latter. At the same time the doctor is susceptible of movement with relation to the couch roll, being yieldingly pressed against the face of 10 the latter by means of the weighted arms 52, the pressure of which may be adjusted by adjusting the position of the weights thereon.

One feature of novelty is the provision 20 of means whereby the decker may be rotated in either direction. Under some conditions it appears to be desirable to rotate the screen drum in the pulp tank in the direction of the entering stock and under 25 other conditions to rotate the drum away from the entering stock. The described embodiment of my invention is so arranged that this rotation may be had in either direction.

The adjustments of the machine have been 30 described for rotation of the cylinder and the couch roll which correspond to the arrow heads shown in Fig. 1, that is to say for a rotation of the screen drum toward the stock 35 entering the tank. If it is desired to reverse the rotation of the screen drum and the couch roll, the position of the doctor with reference to the couch roll is reversed, the 40 doctor in its reverse position being shown in Fig. 7.

To provide for this reversal, each tilting frame 32 has a projection extending rearwardly and downwardly and carrying the 45 boss 57 which corresponds to the boss 50 at the top of the frame. To reverse the position of the doctor, the trunnion pins 51 which support the slotted supporting arms for the doctor are withdrawn from the 50 bosses 53 and placed in the bosses 57, giving the doctor the position shown in Fig. 7. When thus located the doctor is in a position to remove the pulp from the couch roll when rotating in a right-handed direction, 55 as viewed in Fig. 1.

The couch roll may be driven by any suitable means, but herein is driven by the driving belt 60 (see Fig. 2) which passes over the driving pulley 61 (see Figs. 2 and 3) 60 on the couch roll shaft 30 and also over a driving pulley 62 at one end of the main drive shaft 7. The diameters of the driving and driven pulleys and those of the driving gears for the main cylinder are preferably 65 selected so that the couch roll is driven at a

surface speed which is slightly greater than that of the cylinder, this being found to give the most effective action for the couch roll and at the same time lengthening the life and durability of the screen. In order 70 to adjust this surface speed as required, the pulley 61 may be expansible in form, or any other speed adjusting device may be employed if desired.

In order to impart greater driving effort 75 to the couch roll driving belt from the driving pulley 62, the idler pulley 63 may be employed carried by the swinging arm 64 mounted on the main drive shaft 7 and having secured thereto the weighted arm 80 65 provided with the counterweight 66 which tends to draw the idler pulley down into contact with the belt 61 and both tighten the same and increase the driving effort. When the machine is operated under 85 conditions where the rotation of the cylinder mold 5 is reversed, the idler pulley 63 and the weighted arm are adjusted in relation to the belt to some such position 90 as is shown in Fig. 8.

Under some conditions of operation it may be desirable to withdraw the thickened deckered stock in the stock tank and to convey it at times into the inlet stock tank 95 or at other times to the receptacle which receives the thickened stock from the couch roll, a portion of the stock in the tank being thick enough to pass out with the thickened stock. To permit the overflow of the thickened deckered stock either to the inlet tank or to the conveyer tank 25 at will, I have provided an overflow plate 70 near the top of the stock tank and at the opposite side thereof from the stock supply passages. On 100 the outside of the stock tank and below the overflow plate 70 there is provided a removable deflector plate 71. When the plate 71 is in position, the overflow from the tank will pass directly on to the plate 71 and into the conveyer tank 25 together with the thickened stock which is removed by the doctor from the couch roll and gravitates down the deflector plates 23 and 24. As 105 stated, under certain conditions the overflow from the tank is thick enough to pass out with the thickened stock from the couch roll. For example, when the decker is operated with a left-handed rotation of the cylinder mold, as viewed in Fig. 1, the stock 110

may be thick enough at the overflow plate 70 to warrant the deflection of the thickened overflow into the conveyer tank 25. The plate 71, however, is removable and, when removed, the overflow will gravitate 115 into a suitably positioned underlying passage 72, and through suitable passages (not herein shown) into the inlet stock tank. When the plate or gate 71 is removed, therefore, the overflow is carried back into the 120 125 130

inlet stock and with the stock supply into the tank 10.

Before the decker is shut down it is necessary to remove the stock from the cylinder mold in order that it will not dry thereon and clog up or close the openings in the screen. Such removal may be readily accomplished by means of a steam jet applied to the ascending side of the cylinder over 10 the side which approaches the couch roll. In case left-handed rotation (as viewed in Fig. 1) however, is resorted to, it is ordinarily difficult or impossible to apply a steam jet to the ascending side of the cylinder 15 since the latter is concealed or covered by the conveyer or deflecting plates from the couch roll. In the described form of decker, however, provision is made for the insertion of a steam jet through a suitable opening, 20 such opening being herein provided between the two stages or plates 23 and 24 of the two-stage deflector. The space between such deflecting plates is large enough to permit the insertion of a steam nozzle between 25 the same and provide a blast of steam against the cylinder onto the ascending side of the screen to clean it.

While I have herein shown and described for purposes of illustration one specific embodiment of the invention, it is to be understood that extensive deviations may be made therefrom and from the mechanical details herein shown, and from the relative arrangement of parts, all without departing 35 from the spirit of the invention.

Claims.

1. In a paper making machine, the combination with a pulp tank and a rotary screen therein, of an overflow tank for the 40 screened white water, and normally closed means for discharging the pulp residue of the tank at will to the white water chamber.

2. The combination with a pulp tank, a rotary screen therein, a chamber to receive 45 the screened white water on the pulp tank, and means for opening the pulp tank directly to the white water chamber.

3. The combination of a pulp tank, a rotary screen therein, discharge passages to receive 50 the screened white water from the tank, a pulp receiving receptacle, and means to drain the pulp residue from the tank into the receptacle.

4. In a decker, a cylinder mold, a pulp 55 tank, a recovery receptacle, and means for draining the pulp residue into the recovery receptacle.

5. In a paper machine the combination 60 with a stock tank, a rotary screen drum therein, a couch roll and a doctor co-operating with the couch roll and having an edge adjustable in a plane tangential to the couch roll.

6. In a paper machine the combination 65 with a screen drum and couch roll, the lat-

ter movable toward and from the drum, of a doctor movable with the roll and also adjustable with relation thereto, thereby maintaining the angular relation of the doctor to the roll substantially the same in the different positions of the roll. 70

7. In a paper machine, the combination with a stock tank, a rotary screen drum therein, a couch roll, one or more supporting members for the couch roll adjustable 75 to vary the pressure of the roll upon the screen drum, and a doctor also carried by said supporting members but adjustable along a substantially tangential line with reference to the couch roll. 80

8. In a paper machine, the combination with a couch roll of a doctor blade, supporting members on which said doctor blade is adjustable to vary the region of contact between the doctor blade and the couch roll, 85 and means for swinging the doctor blade supports to press the doctor blade against the couch roll.

9. In a paper machine, the combination with a stock tank, a rotary screen drum, a 90 couch roll, of a doctor blade, supporting members therefor on which said doctor blade is adjustable to vary the region of contact between the same and the couch roll, means supporting said supporting members for 95 swinging movement, and a weighted arm to swing the members to press the doctor blade against the couch roll.

10. In a paper machine, the combination with a screen drum of a couch roll, means 100 for rotating the drum and roll, a doctor, means for supporting the same in position to remove the pulp from the couch roll when the latter is rotated in one direction, and means to support the doctor blade in a different relation to the couch roll to remove the pulp therefrom when the cylinder and couch roll are rotated in the opposite direction. 105

11. In a paper machine, the combination 110 with a couch roll of a doctor blade therefor having a reversible position whereby it may be used with the couch roll irrespective of the direction of rotation of the latter.

12. A paper machine having a pulp tank, 115 a rotary screen drum, a couch roll co-operating therewith, and means to move the pulp from the couch roll, the said machine being capable of operation with the drum and couch roll rotated in either direction. 120

13. In a paper machine, a couch roll having a reversible doctor blade to adapt itself to the rotation of the couch roll in either direction.

14. In a paper machine, the combination 125 with a screen drum of a couch roll, a tilting frame, means for adjusting the frame to vary the pressure of the couch roll on the screen drum, and a plurality of doctor blade supports carried by said frame whereby the 130

doctor may be operatively presented to the couch roll irrespective of the direction of rotation of the latter.

15. In a paper machine, the combination 5 with a pulp supply tank, a rotary screen drum therein, a couch roll, means to supply stock to said tank, a receptacle to receive thickened stock from the couch roll, said tank having an overflow, and means to divert the overflow to the receptacle for the thickened stock at will.

16. In a paper machine, the combination 15 with a pulp supply tank, a rotary screen drum therein, a couch roll, means to supply stock to said tank, a receptacle to receive thickened stock from the couch roll, said tank having an overflow, and means to divert the overflow to the receptacle for the thickened stock or to the pulp supply at will.

20 17. In a paper machine, the combination with a pulp tank, a rotary screen drum therein, a couch roll, a receptacle to receive thickened stock from the couch roll, said tank having an overflow passage to convey 25 the overflow into the stock supply tank, and a movable wall or gate to divert the overflow at will into the receptacle for the thickened stock.

25 18. In a paper machine, the combination 30 with a pulp tank having a stock supply, a rotary screen drum therein, a couch roll coöperating with the drum, a receptacle to receive the thickened stock, said tank having an overflow and means for conveying 35 the overflow to the stock supply.

19. A paper machine having a pulp tank, a rotary screen therein, a couch roll, a doctor and a receptacle for the thickened stock from the couch roll, said tank having 40 also an overflow and means to convey the overflow at will, either to the said receptacle or to a passage leading elsewhere than to the receptacle for the thickened stock.

20. In a paper machine, the combination 45 with a tank 10, a screen drum 5, and a couch roll 21, of the overflow plate 70, gate 71 and passage 72.

21. In a paper machine, the combination 50 with a pulp tank of a rotary screen drum, a couch roll coöperating therewith, a doctor operatively related to the couch roll, and a deflector to raise the thickened stock from the couch roll, said deflector having a longitudinally extending, cleaning opening 55 therein whereby the surface of the cylinder may be cleaned.

22. A paper machine having a pulp tank, a rotary screen drum therein, a couch roll and doctor, and a two-stage deflector to 60 raise the thickened stock permitting cleaning access to the screen drum.

23. In a paper machine, the combination 65 with a pulp tank having means for supplying stock at one side thereof, a rotary screen in said tank, a couch roll coöperating with

the screen, a doctor operatively related to the couch roll for removing the thickened pulp, means at the opposite side of the tank from the stock supply means for conveying the thickened pulp, and an opening at said 70 opposite side through which a suitable cleaning agent may be applied to the screen.

24. In a paper machine, the combination 75 with a tank 10, a screen 5, couch roll 21 and doctor 22 of the two-part deflector 23, 24.

25. In a paper machine the combination with a couch roll of a screen drum, said screen being driven by means other than the couch roll, a supporting frame for the couch roll which holds the latter yieldably 80 toward the drum and means for accurately adjusting the frame positively to move the couch roll more or less away from the frame, said couch roll being thereby held at an adjustable minimum distance from the 85 drum but movable away from the drum.

26. In a paper machine, the combination 90 with a screen drum of a couch roll, a supporting frame for the couch roll which permits the latter to gravitate in contact with the drum, and a threaded adjusting device for positively lifting the couch roll more or less away from the drum.

27. In a paper machine, the combination 95 with a pulp tank, a screen drum therein, a couch roll coöperating with the drum, a tilting frame for the couch roll, a fixed support for the tilting frame, a threaded adjusting member engaging the tilting frame and also the fixed supporting member, and 100 means for turning said threaded adjusting member.

28. The combination with a cylinder drum, of a couch roll, a couch roll supporting frame and means for adjusting said 105 frame comprising a threaded adjusting member having engagement with the couch roll frame to a compression spring.

29. In a paper machine, the combination 110 with a pulp tank, a rotary screen therein, a chamber adapted to receive the strained liquid which is passed from the tank through the screen, and means at will for conveying to said receptacle the unscreened residue in said tank.

30. A paper machine having a pulp tank, a screen therein, an overflow chamber for the strained liquid which has passed from the tank through the screen, and a gate in the lower part of the tank adapted to be 120 opened to open the tank to said overflow chamber.

31. In a paper machine, the combination 125 with a pulp tank, a rotary screen therein, an overflow chamber for the white water, and means for withdrawing the unscreened residue from the bottom of the tank, and conveying it to the white water.

32. In a paper machine, the combination 130 with a stock tank 10, a rotary screen 5, a

6 couch roll 21, a doctor 22, a tangential adjustment holder 54, and a weighted arm 52.

33. In a paper machine, the combination with a tank 10, a screen drum 5, a couch roll 21, a doctor 22, and the supports 50 and 57 for carrying the doctor in opposite relations to the couch roll.

34. In a paper machine, the combination with a tank 10, a rotary screen 5, a couch roll 21, a doctor 22, a deflector 24, and the cleaning opening therein.

35. In a paper machine, the combination with a drum, a couch roll, a couch roll support, and means for adjusting said support at each end simultaneously to adjust the relation of the couch roll to the screen.

36. In a paper machine, the combination with a pulp tank, of a screen, a drum, a couch roll, a couch roll supporting frame,

threaded adjusting devices at opposite ends 20 of said frame, means for turning said devices simultaneously to adjust the couch roll with relation to the screen while maintaining the same parallel therewith.

37. In a paper machine, the combination 25 with a pulp tank, of a screen, a drum, a couch roll, a couch roll supporting frame, threaded adjusting devices at opposite ends of said frame, means for turning said devices simultaneously to adjust the couch 30 roll with relation to the screen while maintaining the same parallel therewith, and a yieldable connection between said adjusting devices and said couch roll support.

In testimony whereof I have signed my 35 name to this specification.

ANTON J. HAUG.
